UNITED STATES PATENT OFFICE.

GEORGE H. DEATON AND WALTER E. NUNN, OF CHICAGO, ILLINOIS, ASSIGNEES TO
GEORGE H. DEATON & COMPANY, OF CHICAGO, ILLINOIS, A CORPORATION OF ILLINOIS.

DESIGN FOR A POCKET SAVINGS BANK.

Application filed July 11, 1921. Serial No. 483,979. Term of patent 14 years.

To all whom it may concern:

Be it known that we, GEORGE H. DEATON and WALTER E. NUNN, citizens of the United States, residing at Chicago, in the county of Cook and State of Illinois, have invented a new, original, and ornamental Design for a Pocket Savings Bank, of which the following is a specification, reference being had to the accompanying drawing, forming a part thereof.

Fig. 2 is a perspective view of the bank.

We claim:

The ornamental design for a pocket savings bank, as shown.

GEORGE H. DEATON.
WALTER E. NUNN.
